JUAN E. ROMAGOSA SANCHEZ, OF SAN JOSE, COSTA RICA.

FLOOR CLEANING AND POLISHING APPARATUS.

Application filed May 7, 1924. Serial No. 711,613.

To all whom it may concern:

Be it known that I, JUAN EVANGELISTA ROMAGOSA SANCHEZ, a citizen of the Republic of Costa Rica, residing at San Jose, in the Republic of Costa Rica, have invented a new and useful Floor Cleaning and Polishing Apparatus, of which the following is a specification.

As far as is known different forms of apparatus which have been used as floor-cleaners, and polishers are defective in that they have been either too soft or a little too hard. The cocoa-nut when dry after it has ripened in full, furnishes just the right material to use as a floor cleaner and polisher. The use of the cocoa-nut as a floor polisher and cleaner economizes time if compared with other things, lasts for many years, and gives a perfect and most beautiful luster to the wooden surfaces to which it is applied, with the advantage, over other similar things, of saving wax or oils used for said purposes. The perfection of the luster obtained is such that after a comparatively short time of the cocoa-nut polishing system, footprints or other marks will not show on the floors.

The invention consists of taking a section of the cocoa-nut and providing it with a convenient and easy managing form of handle. The handle may be secured to the cocoa-nut in numerous different ways, two of which are illustrated.

In the accompanying drawings:

Fig. 1 is a perspective view of the cleaner showing one form of handle;

Fig. 2 is a fragmentary central transverse section;

Fig. 3 is a fragmentary transverse section showing a method of attaching the cocoa-nut;

Fig. 4 is a fragmentary plan view showing another method of attaching the handle;

Fig. 5 is a detail sectional view of the type of handle shown in Fig. 4.

Referring again to the drawings the section of the cocoa-nut husk is designated 10. Said section 10, is secured to a rectangular member 11, by means of wires 12, that are fixed in the cocoa-nut husk 10, and in turn are held to the member 11 by any convenient means 13.

Two pieces 14, running lengthwise of the member 11, and secured thereto by screws 15, act as bearings for the trunnions 16, which are on the T shaped member 17. The stem 18 of this T member has barbs 19, for permanently securing said member in the handle 20.

In the form of handle shown in Figs. 4 and 5, the stem 18^a of the member 17^a is provided with a ball 21 that is adapted to work in a socket 22 attached to the rectangular member 11^a which in turn is secured in any convenient way to the section of the cocoa-nut. This, as is obvious, provides a universal joint attachment for the handle 20^a.

Numerous other convenient ways of attaching the handle may be provided that permit of easy control of the direction desired in the movements of the brush.

This application is a substitute application for an application on the same subject matter, filed April 30, 1921, Serial Number 465,719.

What I claim as new is:

1. In a floor-cleaning and polishing apparatus, the combination of a cupped section of a mature and dry cocoa-nut, a handle and means attaching said handle to the dome of said section.

2. In a floor-cleaning and polishing apparatus, the combination of a section of a mature and dry cocoa-nut, a handle connected to the dome of said section, said connection including a universal joint.

Dated, San Jose, Costa Rica, March 22, 1924.

JUAN E. ROMAGOSA SANCHEZ.
